UNITED STATES PATENT OFFICE.

WILLIAM H. LILLY, OF READING, ASSIGNOR TO HENRY B. GRAULEY, OF PHILADELPHIA, PENNSYLVANIA.

CIGAR-TIP CUTTER.

SPECIFICATION forming part of Letters Patent No. 330,597, dated November 17, 1885.

Application filed June 13, 1885. Serial No. 168,581. (No model.)

To all whom it may concern:

Be it known that I, WILLIAM H. LILLY, a citizen of the United States, residing in the city of Reading, county of Berks, State of Pennsylvania, have invented a new and useful Improvement in Cigar-Tip Cutters, which improvement is fully set forth in the following specification and accompanying drawings, in which—

10 Figure 1 represents a top or plan view of a cigar-tip cutter embodying my invention; Fig. 2 represents a side elevation thereof. Fig. 3 represents a vertical section thereof.

Similar letters of reference represent corresponding parts of the several figures.

15 My invention relates to cigar-cutters; and it consists in certain improvements in the device for which Letters Patent No. 318,995, of date June 2, 1885, were obtained by me, said 20 improvements consisting in constructing the cigar-cutter with a base having a detachable drawer, and also with means of particular form for supporting the spring-guide, in which the plunger operates, and other details, as will 25 be hereinafter fully set forth and described.

30 Referring to the drawings, A represents a stand, and B the base thereof, said stand and base being hollow. C represents a plunger, provided at top with a pad or handle for convenience of depressing the same. Within the stand are blades D, which are attached to the plunger C, and made of spring metal, so that their cutting-edges press closely against the inner face of the stand, and thus easily and 35 nicely cut the cigar-tips introduced through the openings in the sides of the stand. In order to restore the blades to their normal position, I employ a spring, E, which bears upwardly against the plunger C, and is fitted in 40 a guide, F, the latter being supported on a cross-bar, G, which is screwed or otherwise secured to the lower end of the stand A. Within the base B is a drawer, H, for collecting the tips, as severed from the cigars, and on

45 the upper wall of said base is a match-striking surface, J, which may be roughened or in the form of letters, in order to ignite matches struck thereon. The cross-bar G sustains the guide F, as above stated, and leaves a passage on each side thereof, below the openings in 50 the hollow column or stand, as means of communication between said stand and the base B, whereby the tips, when severed, drop through said passages into the drawer, without liability to clog or collect at the base of 55 the column. The bottom board, K, is detachably secured to the base, so that it may be removed and access had to the bar G, for displacing the same and the other interior parts of the stand above said bar for sharpening the 60 blades and supplying a fresh spring, should the old spring break or be of improper tension.

In practice the stand and base are cast in one piece of metal, and the drawer and all 65 other parts, excepting the bottom board, K, are also made of metal, so that a strong, durable, and serviceable device is presented.

I am aware that it is not new to construct a cigar-tip cutter having a drawer, and such 70 I do not broadly claim.

Having thus described my invention, what I claim as new, and desire to secure by Letters Patent, is—

75 In a cigar-tip cutter, a hollow stand with openings in its sides, in combination with a plunger having a spring-guide supported by a cross-bar removably connected with the lower end of the stand, leaving passages at its sides below the opening of the stand, a bottom 80 board removably connected with the bottom of the base, and a hollow base provided with a drawer, all substantially as and for the purpose set forth.

WILLIAM H. LILLY.
